THOMAS MALLEY, OF ALLEGHENY CITY, PENNSYLVANIA.

Letters Patent No. 85,944, dated January 19, 1869.

MACHINE FOR DRYING HAIR.

The Schedule referred to in these Letters Patent and making part of the same.

To all whom it may concern:

Be it known that I, THOMAS MALLEY, of Allegheny City, in the county of Allegheny, and State of Pennsylvania, have invented certain new and useful Improvements in Machine for Drying Hair, and I do hereby declare that the following is a full, clear, and exact description thereof, reference being had to the accompanying drawings, and to the letters of reference marked thereon, which form a part of this specification.

My invention relates to machinery used for "drying hair" for plastering, and other purposes where hair is required.

When hair is scraped from the hides, it is found saturated with lime-water, used in the operation of tanning which has to be removed, and the hair well dried, before it becomes of commercial value. As heretofore hair has been dried, the operation has been performed either by the warmth of the sun, the hair being spread on the ground, else the hair has been dried in kilns, or such like constructions, taking a great deal of manual labor, and also expending much time.

By my devices, hair is dried more thoroughly and quicker, and without comparatively any manual labor.

In the accompanying drawings—

Figure 1, Sheet No. 1, is a plan of my improved machine for drying hair.

Figure 2, a side elevation thereof.

Figure 3, a rear elevation thereof.

Figure 4, Sheet No. 2, a longitudinal section of the same.

Figure 5, a transverse section of the same.

Like letters of reference in the different figures indicate corresponding parts.

To enable others skilled in the art to make and use my invention, I will proceed to describe its construction and operation.

A frame-work, A, of suitable construction, sustains and carries the devices used, on which, and revolving in suitable bearings, is a main driving-shaft, A¹, provided on the one end with a band-wheel, A², and on the other end a spur-pinion, A³, which meshes into and drives a large spur-wheel, A⁴, attached to a horizontal shaft, A⁵, on which is affixed by screws, or such like devices B, an annular cylinder, B¹, having at the end near the spur-wheel A⁴, a flange, B², and at the other end, a circular plate, B³, attached to the frame A, and so arranged, and of such a size, that there will be a space, B⁴, between, in, and around the inner circumference of the cylinder B¹, which is furthermore provided on the inside with four or more rakes or teasers B⁵, made of flat bars, with projecting points, pointing towards the axis of the cylinder B¹. These bars run longitudinally, and are affixed by screws, in any suitable devices.

Attached in a suitable manner to the circular plate

B³, is a pipe, B⁶, passing up over and along the cylinder B¹, until it reaches the outlet or mouth of a fan-casing, C, of ordinary construction, whose inlet C¹ points downward.

The casing C is attached to the pipe B⁶, by means of the hinge C².

The main frame A supports the casing C, inside of which, and revolving in suitable bearings, is a fan-wheel, of ordinary construction, D, by means of a spur-pinion, D¹, affixed to its shaft D², which pinion D¹ is driven by a spur-wheel, D³, attached to a counter-shaft, D⁴, revolving in suitable bearings on a standard, D⁵, on the further extremity of which shaft D⁴ is a spur-pinion, D⁶, moved and revolved by means of the spur-wheel A⁴, before mentioned.

About midway the shaft D⁴ is provided with a bevel-gear wheel, E, which revolves a bevel-gear wheel, E¹, attached to a cross-counter-shaft, E², on which is affixed a gum-roll, E³, pressing against which, and driven by it, by means of its friction, is another gum-roll E⁴, attached to a shaft, E⁵, running parallel with the shaft E², both of which are in an inclined position, the extremities nearest the shaft D⁴ being below, and pointing downward from their other extremities.

Underneath these rolls, and attached in any suitable manner, is a spout or chute, F, of ordinary construction, with its outlet F¹ opening into the inside of the cylinder B¹, above which is a hopper, F², of ordinary construction, supported from the standard D⁵ in a suitable manner, its mouth pointing over and between the rolls E² and E⁴.

The mode of operation with my devices, in drying hair, is as follows, viz:

The hair is placed on the hopper F², motion being then conveyed to the band-wheel A² in any suitable manner, which sets in motion the driving-shaft A¹, with its pinion A³ driving the shaft A⁵ and cylinder B¹, also putting in motion the fan-wheel D, by means of the mechanisms before described; the inlet-pipe C¹ being connected with a hot-air stove, or such like contrivance, as will cause heat to ascend, and make the blast caused by the revolution of the fan D hot. The rolls E² and E⁴ being set in motion at the same time, and by the same operation, draw the wet hair through between their peripheries, squeezing out the water, which flows along the line of rolls E² and E⁴, owing to their inclined position, and falls into where it may be required. The hair having passed through the rolls, falls down into the chute F, and into the cylinder B¹. The rakes B⁵ tease and work the hair, owing to their revolving motion. At the same time the hot blast from the fan D is admitted, by means of the pipe B⁶, permeates the mass, and the heat passes right through. The cylinder B¹ is of such construction and length, that by the time the hair has

passed from the one end to the other, it will be found perfectly dry. The hair falls through the space B⁴ into the receptacle used for its transmission.

Having thus described the nature, construction, and operation of my devices,

What I claim, and desire to secure by Letters Patent, is—

The frame A, shaft A¹, with its operative mechanisms A² and A³, shaft A⁵, and wheel A⁴, cylinder B¹, and rakes B⁵, end plate B³ and screws B, in combination with the rolls E² and E³, with their operative

mechanisms E¹ and E⁴, chute F and hopper F², fan D, casing C, inlet C¹ and outlet B⁶, with the operative mechanisms D¹, D², D³, D⁴, and D⁵, when constructed, arranged, and operating as herein described, and for the purpose set forth.

In testimony that I claim the foregoing as my own, I affix my signature, in presence of two witnesses.

THOMAS MALLEY.
